UNITED STATES PATENT OFFICE

ROBERT C. HOWELL, OF POMPTON LAKES, NEW JERSEY

LOCK FOR INCANDESCENT LAMPS

Application filed June 11, 1928. Serial No. 284,345.

The present invention relates, generally, to a locking arrangement for holding electric lamp bulbs in their sockets; and the invention relates, more particularly, to an electric lamp lock which is automatic in its locking function and which is operable by a magnet to unlock, and the locking arrangement is adaptable for general things other than electric bulbs.

10 An object of the invention is to provide a lock operable by a magnet to open it, which lock has in combination therewith parts for engaging an electric lamp bulb and for connecting it to the lock.

15 Various other objects and advantages of the invention will be obvious from the following particular description of forms of apparatus embodying the invention or from an inspection of the accompanying drawings; 20 and the invention also consists in certain new and useful features of construction and combinations of parts hereinafter set forth and claimed.

25 In the accompanying drawings there are shown for purposes of illustration one form of apparatus with certain modifications thereof embodying the invention, in which:

Fig. 1 is an elevation view in part section; Fig. 2 is a bottom plan view;

30 Fig. 3 is a view taken along the line 3—3 of Fig. 1, looking in the direction of the arrows;

Fig. 4 is a sectional view showing details of the locking arrangement;

35 Fig. 5 is a section view along the line 5—5 of Fig. 4, looking in the direction of the arrows;

Fig. 6 is a plan view of lamp bulb engaging rings; and

40 Fig. 7 is an elevation view of the parts shown in Fig. 6.

In all the above described views like reference characters are used to designate corresponding parts throughout.

45 Referring now to the drawings the reference character 1 indicates an electric lamp socket of the conventional type which holds screwed therein the bulbous lamp globe 2 and a metal shade 3 over said globe 2. Positioned on said globe 2, one above and one

below the largest diameter of the bulb thereof, are the rings 4 and 5 which at one side are held close together by the sleeve hinge 6. At the opposite side said rings 4 and 5 carry, respectively, the stiff metal lugs 7 and 8 which latter have formed therethrough the openings 9 and 10, respectively. Above said openings 9 and 10 said shade 3 has an opening 11 of the same size as openings 9 and 10, and through said openings 9, 10 and 11 there extends a rod 12 which at its lower end has a head 13 and at its upper end an annular notch 14. On said rod 12 between said shade 3 and lug 7 is a compression spring 15 which presses against these two members and tends to hold ring 4, through lug 7, in engaging relation on said lamp 1; but said spring 15 can be omitted.

On the upper end of said rod 12 at the upper side of said shade 3 is a locking arrangement, for engaging the upper side of said shade 3 and locking engagement with said rod 12 at said annular notch 14, comprising a tube 16 closed at one end by the disk 17 secured therein by a drive fit and by having the edges of tube 16 turned over to prevent outward displacement. Adjacent said disk 17, on the inner side therefrom, said tube 16 has formed therethrough a pair of diametrically opposite openings 18 and 19 of a size to admit said rod 12 with a sliding fit. Secured in said tube 16 by drive fit is a sleeve 20 which extends from a point adjacent said openings 18, 19 to a point at a little distance from the other end of tube 16, and which has near its inner end an inner annular shoulder 21. Against the outer end of said sleeve 20 is an annular disc 22 which is held in place by the turned over edges 23 of the end of tube 16. In said sleeve 20 and having sliding fit therewith is the annular washer 24 which is normally held against said shoulder 21 by a compression spring 25 which latter bears at one end against said annular washer 24 and at its other end against said annular disk 22.

Extending centrally through said spring 25 and secured to said annular washer 24 by the pin 26 is the bolt 27 preferably of iron or steel or having its outer end at least of magnetic material. Said bolt has a sliding fit in the central opening of said annular disk 22

in which the outer end of the bolt rests with its outer face flush with the outer face of said disk 22. The inner end of said bolt 27 extends from said annular washer 24 to a point on a line between said openings 18 and 19 and is of a width to have a sliding fit into the annular notch 14 in said rod 12 when the latter is positioned in said openings 18 and 19. The distance of said notch 14 from said head 13 is preferably such that said head 13 holds ring 5 in locking engagement closely against the bottom of the bulb of said lamp 2, when the parts are in locked engagement as shown in the drawings, with said tube 16 lying against the outer side of said shade 3.

Said locking arrangement is positioned on said rod 12 by pushing the end of the latter through said holes 18 and 19, the pointed end of the rod 12 serving to push said bolt 27 back against the compression of said spring 25 until said annular notch 14 comes to a position fully adjacent the end of the bolt when the latter will be pushed by said spring 25 into locking engagement into notch 14 and the end of rod 12 will extend a short distance beyond tube 16.

To unlock the arrangement an electromagnet, or other magnet, is applied to the outer end of said bolt 27 to draw the inner end from engagement with the notch in said rod 12 whereupon the latter can be withdrawn.

It will be of course understood that a plurality of annular notches or other notches similar to notch 14 can be formed in said rod 12 to adapt the device to fit different sizes of lamps, shades, etc.

In Figs. 6 and 7 are shown alternate forms of rings 4 and 5 in which the wire rings 28 and 29 are secured to each other at one side by the sleeve hinge 6 and on the other side have formed integral therewith, respectively, the eyelets 30 and 31, instead of the lugs 7 and 8 of Fig. 1.

From this it can be seen that a strong, locking arrangement is provided which cannot be opened nor the lamp removed therefrom without the use of a strong electromagnet to actuate said bolt 27 to unlock it from said rod 12.

While I have shown and described and have pointed out in the annexed claims certain novel features of the invention, it will be understood that various omissions, substitutions and changes in the forms and details of the devices illustrated and in its use and operation may be made by those skilled in the art without departing from the spirit of the invention.

Having thus described my invention, what I claim and desire to protect by Letters Patent is:

1. In combination with an electric socket, adapted to hold a lamp having a bulbous globe; a pair of rings adapted to be positioned in engaging relation about said lamp,

one above and the other below the part of largest diameter of the bulb of said lamp globe; said rings being closely adjacent each other at one side thereof and having a hinge which secures them together at said side; an eyelet on each of said rings on the opposite side; a member fixed to said socket and having an opening therethrough at a point above said part of largest diameter of said lamp globe; a rod extending through said eyelets and said opening with a close fit and having a stop member engaging the lower of said eyelets and a shoulder thereon at a point above said fixed member; and a locking means for engaging said rod at said shoulder having a spring actuated bolt, which bolt has a magnetic portion adapted to be moved by a magnet to open said bolt.

2. In combination with an electric light socket; a lamp in said socket; a member fixed to said socket and having an opening therethrough; a rod having means thereon adapted to engage said lamp and limit it against movement from said socket, said rod having a shoulder at its upper end and being adapted to be inserted through said opening in said fixed member to bring said shoulder above said fixed member; and a locking means for engaging said rod at said shoulder having a spring actuated bolt, which bolt has a magnetic portion adapted to be moved by a magnet to open said bolt.

3. In combination with an electric light socket adapted to hold a lamp; a member fixed to said socket and having an opening therethrough; a rod having means thereon adapted to engage a lamp in said socket and limit it against movement from said socket, said rod having a shoulder at its upper end and being adapted to be inserted through said opening in said fixed member to bring said shoulder above said fixed member; and a locking means for engaging said rod at said shoulder having a spring actuated bolt, which bolt has a magnetic portion adapted to be moved by a magnet to open said bolt.

4. In combination with an electric light socket, a lamp shade affixed thereto, a lamp in said socket having a bulbous globe, a ring engaging the free end of said lamp globe and having an eyelet formed at one side thereof, a headed rod extending through said eyelet and positioned within said shade and having its head engaging said eyelet, said shade having an aperture therein through which a portion of said rod extends, said projecting portion of the rod having an annular notch therein, a hollow member closed at one end and having a closure fixture across its other end with an opening therethrough and having a pair of oppositely spaced transverse openings through the walls thereof adjacent said closed end and through which said rod extends with a sliding fit, a locking armature positioned within said hollow member and

projecting at one end into the opening in said closure fixture and at its other end into said notch in said rod, and spring means positioned within said member and cooperating with said closure fixture and armature to retain the end thereof in engagement with the notch of said rod, to thereby lock the lamp globe within its socket.

5. In combination with an electric light socket for holding a lamp, a pair of rings positioned in engaging relation about said lamp, one above and the other below the part of the largest diameter of said lamp globe, said rings being connected closely adjacent each other at one side thereof and having eyelets at their opposite sides, a member fixed to said socket and having an opening therethrough in line with the eyelets of said rings, a rod extending through said eyelets and said opening and having a headed portion engaging the outer of said eyelets and a notch therein above said member, and a hollow member mounted on said rod in locking engagement therewith and engaging said fixed member, to thereby retain said globe within its socket.

In testimony that I claim the invention set forth above I have hereunto set my hand this 24th day of May, 1928.

ROBERT C. HOWELL.
